UNITED STATES PATENT OFFICE

1,967,362

STRIP-SERVING MACHINE

Gustaf E. Johnson, Chicago, Ill., assignor to Metal Specialties Manufacturing Company, Chicago, Ill., a corporation of Illinois

Application June 13, 1931, Serial No. 544,269

2 Claims. (Cl. 91—41.5)

This invention relates particularly to machines adapted to the purpose of serving strips of gummed tape, or the like.

The primary object is to provide improved strip feed means, coating in an improved manner with strip-severing means.

In accordance with the preferred embodiment of the present invention, a feed wheel is journaled on a rock-shaft and is actuated therefrom through the medium of a ratchet device; and the rock-shaft serves also to actuate a cutter, the relation between the elements being such that the actuation of the feed wheel ceases before the cutter strikes the paper strip. Thus, the paper is not caused to jam against the knife and there is no danger of the paper being caused to catch in the slot through which the knife works.

The invention is illustrated in a preferred embodiment in the accompanying drawings, in which:

Fig. 1 is a broken side elevational view of a machine embodying the invention; Fig. 2, a broken side vertical sectional view, taken as indicated at line 2 of Fig. 3; Fig. 3, a broken plan of the machine with the top portion removed, showing the feed wheel and operating crank; Fig. 4, a front vertical sectional view, taken as indicated at line 4—4 of Fig. 2; Fig. 5, a broken plan view of the machine; Fig. 6, a detail sectional view of the top-plate, taken as indicated at line 6 of Fig. 5; and Fig. 7, a broken vertical sectional view showing the feed wheel and the ratchet release cam.

In the preferred construction illustrated, A designates a frame or casing comprising a base member A', a surmounting member A² rigidly secured thereon, and a cover member A³ pivotally connected to the member A²; B, an oscillatable main shaft journaled in the member A' equipped with an actuating handle B', the stroke of which may be regulated by an adjustable gauge B²; C, a feed-wheel journaled on the shaft B and equipped with a ratchet wheel C'; D, a spring pressed idle feed-roll which coacts with the feed-wheel C; E, a roll of gummed tape from which the strip E' passes to the feed rolls; F, a cutting mechanism comprising a blade-equipped lever F', a link F², and an actuating arm F³; and G, a water-font removable through the front end of the machine.

In the embodiment of the invention shown, the frame A is composed of elongated hollow castings mounted one upon another. The main part

of the frame comprises the base casting A' and the surmounting casting A².

The main actuating rock-shaft B is journaled in the casting A' and may be rocked by means of the crank or handle B'. The shaft is urged in a counterclock-wise direction by a coil spring 10, one end of which engages a capped stud 11 mounted on the frame A' and the other end is attached to a pawl-actuating arm 12, which, in turn, is clamped to the shaft B by means of bolt 13 and nut 13^a. Near the end of the arm 12, a pawl 14 is mounted on a pivot 15. A coil spring 16 is attached to the tail-portion 14^a of the pawl 14, and to the arm 12, so as to normally urge the pawl into engagement with notches 17 in the ratchet wheel C'. The surmounting frame member A² affords a fixed cam 18 which is positioned in the path of the tail-portion 14^a of the pawl so as to release the ratchet when the pawl is oscillated beyond that position. The opposite side of the cam-supporting portion of the frame forms the throat portion of the tape chamber.

The upper portion of the frame housing A² is provided with an opening 20, through which the feed-wheel C engages the strip E'. An idle feed-roll D is journaled in a carriage 21 which in turn is pivoted to the frame A² by means of the shaft 22 and is provided with springs 23 which serve to press the feed-roll D against the strip E' and the underlying feed-wheel C. A rubber roll 24, on the shaft 22, serves as a cushion-stop for the cover member A³.

A guide-plate 25 serves to keep the strip from buckling as it advances from between the feed-rolls over the top-wall of the housing A². A spring-clip 25^a is riveted to the plate and serves to retain it loosely in proper position.

The cutter mechanism F is located near the front of the machine and is supported by a slotted plate 30 which is fastened to the frame A² by means of screws 30^a. The cutter-lever F' is pivotally connected at one end to a bifurcated upright 31 which is fastened to the mounting plate 30 by means of a nut 31^a. The lever is provided with a pointed knife blade 32, which operates through a slot in the plate, and is fastened to the lever by means of a clamping bar 33 and screws 33^a. The free end of the lever has a depending guide member 34 which slides freely in a small slot 35 in the mounting plate. The lever is actuated by means of the link F² which is connected to the long end of the H shaped actuating arm F³, as shown in Fig. 3. The legs 36 of the arm F³ are freely

journalled on the shaft B. The transverse connecting-portion 37 of the arm is provided with a pair of rearwardly extending prongs 37^a, and a tension spring 38 is suspended from a capped 5 stud 39 on the frame A² and is attached to the arm at 37^b so as to urge the arm and cutter-lever into their uppermost positions.

A lost-motion arm 40 is clamped to the shaft B by means of a bolt 41 and nut 41^a, and the 10 end of the arm 40^a is turned over to form a lug which will engage a prong 37^a and depress the cutter-blade when the shaft is rotated beyond a certain position.

The water-font G is of the usual type and 15 supports a moistener which is provided with a presser member 42, serving to press the strip E' into engagement with a wick 43. The font is supported by a plate 44 which is fastened to the base member A' by means of machine screws 20 44^a. The front edge of the base member is recessed to receive a compression spring 45 and a plunger 46 having an upwardly extending lip 46^a which may be depressed to remove the font from the machine.

25 The machine is loaded by placing a roll of gummed paper in the chamber provided in the rear of the machine and a strip E' threaded from the supply roll, between the feed rollers and under the plate 25, to the front of the machine. After filling the font with water, the 30 machine is ready for operation.

To operate the machine, the handle B' is drawn forwardly, which will cause the following 35 actions: the pawl 14 engages the ratchet and causes the feed roll to advance the strip forwardly from under the blade 32 until the tail-portion of the pawl 14^a engages and is depressed by the cam 18, thereby disengaging the ratchet; during that portion of the stroke the lost-motion 40 arm 40 has been advancing towards the prongs 37^a and just as the ratchet releases, the arm makes contact with the prongs; continuance of the stroke presses the arm F³ downward, and through link F² and lever F' the blade is lowered 45 and the strip severed. Upon release of the arm B' the springs will return the parts to their

initial positions, as will be readily understood. It will be noted that during the cutting operation the feed wheel is not operating, and accordingly the strip is not forced to buckle in back of the knife blade.

80 The foregoing detailed description has been given for clearness of understanding only, and no unnecessary limitations should be understood therefrom, but the appended claims should be construed as broadly as permissible, in view of the prior art.

85 What I regard as new, and desire to secure by Letters Patent, is:

1. In combination in a machine of the character set forth: a frame having a throat over which a strip may be led; an actuating rock-shaft journalled in said frame and provided with an arm; a feed wheel and associated ratchet device journalled on said shaft; a strip-severing cutter; an actuating lever journalled on said shaft and linked to said cutter; lost-motion connections between the arm on said rock-shaft and said lever; and a cam segment carried by said throat for disconnecting the ratchet device before conclusion of the working stroke of the 90 rock-shaft.

2. In a machine of the character set forth: a frame having a water fount housing and a throat from which a strip may be led over said housing; a water fount mounted in said housing and equipped with a moistener adapted to moisten a strip fed thereover; a guide-plate for said strip having a spring-clip adapted to snap onto the side walls of the housing; an actuating rock-shaft journalled in said frame and provided with an arm; a feed-wheel associated ratchet device journalled on said shaft; a strip-severing cutter disposed above the housing; an actuating lever journalled on said shaft and linked to said cutter; lost motion connections 105 between said arm and said lever; and a cam segment carried by said throat for disconnecting the ratchet device before conclusion of the 110 working stroke of the rock-shaft.
